UNITED STATES PATENT OFFICE.

ALBERT E. READE, OF PETERSBURG, VIRGINIA.

ADJUSTABLE SPARK-GAP.

1,255,687.

Specification of Letters Patent.

Patented Feb. 5, 1918.

Application filed June 6, 1916. Serial No. 102,554.

To all whom it may concern:

Be it known that I, ALBERT E. READE, a citizen of the United States of America, residing at Petersburg, in the county of Dinwiddie and State of Virginia, have invented certain new and useful Improvements in Adjustable Spark-Gaps, of which the following is a specification, reference being had thereto to the accompanying drawing.

19 This invention relates to an adjustable spark gap for spark plugs which is constructed so as to cause the device to facilitate the even running of an engine as well as permitting comparatively dirty spark 15 plugs to operate easily and to keep new spark plugs clean.

Another object of this invention is the production of an adjustable spark gap which is mounted upon the outer end of a spark 20 plug so that the spark plate being carried upon the insulating strip may be held in an adjusted position with respect to the upper end of the spark plug upon which the nut is carried, thereby providing sufficient space 25 for the passage of an electric current therebetween for producing a spark, the device being adjustable so that it may be used in connection with currents of different voltage.

30 With these and other objects in view this invention consists of certain novel combinations, constructions, and arrangements of parts as will be hereinafter fully described and claimed.

35 In the accompanying drawing:—

Figure 1 is a side elevation of the adjustable spark gap, showing the same mounted upon a spark plug.

Fig. 2 is a top plan view of the device. 40 Fig. 3 is a longitudinal section through the adjustable spark gap, showing the same mounted upon a spark plug also shown in section.

Fig. 4 is a detail perspective view of the 45 insulating strip.

Fig. 5 is a detail perspective view of the plate.

Referring to the accompanying drawing by numerals it will be seen that the adjustable spark gap comprises an insulating strip 1 which is elongated although, of course, it is obvious that the same may be of any desired shape. This insulating strip 1 has the openings 2 formed adjacent one 50 end thereof and a slot 3 formed adjacent its opposite end. The plate 4 has openings 5 formed therein, which openings 5 are adapted to register with the openings 2 formed in the insulating strip, since this plate 4 is adapted to be carried upon this strip 1.

55 The bolt 6 having a nut 7 is adapted to be passed through a plurality of these openings, as shown clearly in Fig. 3, for assisting in retaining the plate in a fixed position upon the insulating strip. The binding post 8 passes through the remaining openings 2 and 5, and has a nut thereon, shown at 9, for holding the same in a fixed position, whereby the bolt 6 and the binding post 8 60 will positively hold the plate 4 upon the insulating strip 1. The wire 10 may be held in engagement with the binding post 8 by means of the binding nut 11, when the device is in operation.

75 The spark plug as indicated at 12 may be of any desired construction and has the sparking pole 13 extending therethrough which also has a nut 14 adjacent its upper end. This upper threaded end 15 of the 80 pole 13 passes through the slot 3 of the insulating strip 1 and carries the binding nut 16.

75 In the spark plugs ordinarily used it is well known that the plugs very frequently 85 become dirty due to various reasons, which frequently causes short circuits and prevents the smooth and even running of the engine owing to the irregular sparking. This device, however, is to be attached in the usual 90 manner to the cylinder of the engine and the wire 10 applied as above set forth. The current will pass through the binding post over the plate 4 to the upwardly extending neck 17 and then to the depending lip 18 95 formed upon the plate. It will be remembered that as long as the plate 4 is held in a fixed position by means of the bolt 6 and the binding post 8 upon the insulating strip it will be held so as to move whenever the 100 insulating strip 1 is moved. If it is desired to move the lip 18 to a point very close to the binding nut 16 it will be seen that the binding nut may be moved upon the threaded upper end 15 of the pole 13, thus allowing 105 the insulating strip 1 to be moved for a short distance owing to the extension of the threaded upper end 15 of the pole 18 through the slot 3 of the insulating strip 1. When the strip has been moved so as to 110 cause the lip 18 to be moved to a position desired, the nut 16 may be again tightened.

upon the strip for holding the strip in an adjusted set position. Thus, it will be seen that if a low voltage current is used the current may easily jump the space, causing a spark between the lip 18 and the nut 16. It is, of course, obvious that the current will pass down through the pole 13 for causing a spark within the cylinder and as the spark plug is mounted upon the cylinder a complete circuit is formed. If a comparatively high voltage current is used the nut 16 may be loosened so as to permit the insulating strip 1 to be moved as far as possible in one direction so as to move the lip 18 of the plate 4 as far as possible from the nut 16. Of course, it is intended that in such an action the current will be of sufficient strength to jump the space between the lip and the nut so as to cause a proper 20 sparking circuit.

From the foregoing description it will be seen that a very simple and efficient adjustable spark gap has been provided which is constructed so as to be easily carried upon the upper end of an ordinary spark plug for inducing an electric current to pass through the spark plug evenly at predetermined intervals for causing the proper 25 sparking within the cylinder, whereby the engine may be caused to run rapidly and easily, while the operation of this device 30 will cause the plug to remain clean. Furthermore, it will be seen that simply by

the adjustment of the nut 16 and the insulating strip 1 the adjustable spark gap may be moved to a position desired and retained in this adjusted set position so that current of different voltage may be passed over the device for properly sparking and at the same time facilitating the operation of the engine.

What is claimed is:—

In a device of the class described, the combination of a plate with an insulating strip, said plate adapted to rest upon said insulating strip, a bolt passing through said plate for assisting in retaining the same upon said strip, a binding post passing through said strip and plate, a wire retaining means carried by said binding post, whereby an electric current may be supplied to said plate, said plate formed from a single sheet of metal and bent so as to provide an upwardly extending neck, said neck terminating in a depending tapering lip, 55 said strip provided with an elongated slot, so that the upper end of a spark plug may be passed therethrough, so as to permit the strip to be moved to an adjusted position, thereby permitting currents of different 60 voltage to be used with the device for causing sparking at the outer end of the plug.

In testimony whereof I hereunto affix my signature.

ALBERT E. READE.
